GAS GENERATOR.

1,422,938.

Specification of Letters Patent.

Patented July 18, 1922.

Application filed November 23, 1918. Serial No. 263,908.

To all whom it may concern:

Be it known that I, PARMER DORSEY, a citizen of the United States, residing in the city of Wichita, in the county of Sedgwick and State of Kansas, have invented a new and useful Improvement in Gas Generators, of which the following is a specification.

This invention relates more particularly to acetylene or other like gas generators. 10 It has for its objects to provide a simple and efficient device for feeding the carbide or equivalent gas-producing constituent or substance to the generator, which is automatic in action and controlled by the pressure in the generator, whereby to maintain a working supply of gas at a pressure above a certain predetermined minimum; and to attain certain advantages as will hereinafter more fully appear.

20 The invention consists in the parts and in the combinations and arrangements of parts hereinafter described and claimed.

The accompanying drawing illustrates a vertical section of the upper portion of an ordinary acetylene gas generator tank as equipped for a practical application of the present invention.

In said drawing, the numeral 1 designates the generator tank, suspended in the upper portion of which, from the head 2, is a hopper 3 in which the carbide or equivalent substance is placed in the heretofore customary condition and manner, but delivered therefrom according to the present invention. 30 It may be here stated that all other component parts or appliances of the generator not concerned directly in this invention are omitted from the drawing, as the same may be of any desired or customary construction and arrangement.

40 As shown, the upper portion of the hopper 3 is generally cylindrical, while the lower portion is frusto-conical, as at 4, and provided with a depending outlet portion or restricted spout 5. Just above the outlet is a conoidal baffle or deflector 6 which is supported in spaced relation to the tapered bottom wall of the hopper by spider arms 7. This baffle affords a support for the mass of carbide in the hopper and prevents choking of the outlet, as only a limited quantity of the carbide at a time passes through the annular space between the margin of the baffle and the shell of the hopper.

50 Cooperating with the end of the spout 5 is

a valve 8 comprising a plate having its opposite end portions flanged, as at 9, and riveted to the side walls 10 of a dumping box or receptacle 11. As shown, this device is hingedly supported on a transverse rod 12 which extends through ears 13 on the spout 5. Extending from one of the side walls 10 of the receptacle is a lever arm 14 having a weight 15 which is preferably adjustable thereon and proportioned so as to yieldably hold the valve 8 in closed position with the weight of the carbide in the spout thereon.

Preferably, though not necessarily so, the end of the spout 5 is bevelled, as shown, so that the valve 8 is correspondingly inclined when in closed position, but, in any case, whether the valve be normally horizontal or inclined in its closed position, the bottom wall of the dumping box or receptacle 11 must be at a relatively steep inclination, so that any loose substance thereon will slide readily therefrom.

Secured to the end wall of the dumping box is a bucket or receptacle 16 for the reception of water or other suitable liquid, as will be presently described; said bucket being of such capacity as to receive a sufficient quantity of the liquid to overbalance the weight 15 and thereby tilt the box 11 and open the valve 8 to release the carbide from the spout 5.

Extending through the head 2 of the tank 1 is a tube 17, the inner end of which reaches in proximity to, and directly above, the bucket 16, while its outer end portion is flared, as at 18, and has an open housing or supporting frame 19 secured thereon with a diaphragm 20 between. The diaphragm carries a rod or stem 21 which extends downward, through the tube 17 and has a valve member 22 at its end to engage a suitable seat 23 provided therefor at the corresponding end of the tube, said valve being seated when the tank 1 is charged with gas to a certain pressure, the pressure acting upon both the diaphragm and valve, as will presently more fully appear, and against the pressure of a spring 24 which is opposed to the diaphragm in the housing or supporting frame 19 and regulated by the manipulation of an adjusting screw 25.

Connecting the tube 17 with the bottom of a tank 26 containing water or other suitable liquid, is a pipe 27 having a cut-off valve 28; while another pipe 29 is provided to afford

communication between the top of said tank 26 and the top of the generator tank 1, so as to equalize the pressure in the two tanks.

A suitable device is preferably provided to 5 manually actuate the dumping box 11, either to initially charge the generator or to loosen said box in case it should happen to stick during the automatic operation thereof, as will be presently described. As shown, it 10 comprises a rod 30, having a handle 31 on its outer end and slidably fitted through a stuffing box 32 on the head 2, and extended through an aperture 33 in the tapered bottom portion 4 of the hopper as a guide, its 15 inner end portion being formed with an offset 34 or otherwise provided to afford two opposed shoulders 35, 36, to engage the lever arm 14 on opposite sides when the rod is moved endwise in either direction, said 20 shoulders 35, 36, being obviously spaced apart sufficiently to permit the lever arm 14 to move freely between them during the automatic operation of the dumping box 11.

In the operation of the generator according to the present invention, the spring 24 is 25 adjusted at the start to resist the desired minimum pressure to be raised in the tank 1, and the valve 22 is thereby opened.

The initial charge of carbide may be delivered from the spout 5 of the hopper either 30 by operating the rod 30 manually or opening the cut-off valve 28 in the pipe 27 which connects the water supply tank 26 and the tube 17. The dumping box 11 will be first tilted 35 to the position shown in broken lines either by lifting the rod 30 or the filling of the bucket 16, as the case may be, so that the carbide released during the opening of the valve 8 thereby, will fall into the box. In 40 this position of the box 11, it is noted that its bottom wall is substantially horizontal or inclined slightly downward towards the end wall, so that the carbide remains therein until the box is brought back to original or 45 dumping position shown in full lines, at which time the charge is dumped into the body of water or liquid in the tank 1 and where it is decomposed and serves its function in the generation of the gas as is well 50 known in this art.

The return of the dumping box 11 to original or dumping position is accomplished by forcing the rod 30 downward, in the case of manual operation, or by the weight 15, 55 when the liquid from the tank 26 is used in the bucket 16, and discharged therefrom.

This charging operation is continued until the pressure of the gas generated in the tank 1, acting upon the diaphragm 20, overpowers 60 the spring 24 and closes the valve 22, after which the operation of the generator is automatic, for as soon as the pressure in the tank 1 falls below that of the spring 24, the valve 22 is again opened, thereby admitting 65 the water to the bucket 16; and the opera-

tion of the dumping box 11 is carried on to deliver the carbide from the hopper until the pressure is raised sufficiently to close the valve 22.

The operation of the dumping box 11 is 70 relatively quick. That is, the instant the bucket 16 is weighted by the water therein sufficiently to overcome the weight 15, the box 11 drops suddenly to the position shown by the broken lines, and as the water is 75 almost immediately discharged from the bucket, the return movement of the box is just as quickly brought about by the weight 15. Consequently, there is no undue waste of the water from the tank 26, and the respective charges of carbide are of regular 80 uniformity in measure.

Should the dumping box 11 accidentally stick during its operation, the rod 30 can be manipulated to loosen or move it to receiving or dumping position, as the case may be. 85

When the generator is not in use, the cut-off valve 28 is closed; and to prevent the operation of the dumping box 11 and consequent generation of gas in the tank 1 at this 90 time, in case there should be any leakage through the valve 22, an aperture 37 may be provided in the bucket 16 of sufficient capacity to drain off such leakage falling into the bucket, and yet permit the bucket to fill 95 when the valve 22 is opened to supply the full working volume of the water during the operation of the generator.

Obviously, the structure admits of considerable modification without departing from 100 the spirit of the invention as defined by the appended claims. Therefore, it is not limited to that shown in the drawing.

What is claimed is:

1. In a gas generator of the character described, a tank, a feed hopper therefor, a dumping charge-delivering device cooperating with the outlet of said hopper, said device having a self-discharging bucket of a filling capacity to overbalance and actuate 110 the device to deliver the charge from the hopper, and automatically operative means, controlled by the pressure of the gas generated in said tank, for supplying a liquid to said bucket, said liquid-supplying means being maintained normally inactive under a predetermined pressure and becoming active 115 only when the pressure decreases.

2. In a gas generator of the character described, a tank, a feed hopper therefor, a combined dumping receptacle and valve mounted hingedly in cooperative relation to the outlet of said hopper, a weighted arm on said receptacle yieldably holding the latter normally in discharging position with the valve in closing relation to the hopper outlet, a bucket on said dumping receptacle in counter relation to and normally outweighed by said weighted arm, but being 125 of a filling capacity to outweigh the latter, 130

- and automatically operative means, controlled by the pressure of the gas generated in said tank, for supplying a liquid to said bucket, said liquid-supplying means being 5 maintained normally inactive under a predetermined pressure and becoming active only when the pressure decreases, whereby said valve is moved to open position, said receptacle to receiving position for the charge 10 as released from the hopper by said valve, and said bucket to discharging position.
3. In a gas generator of the character described, a tank, a feed hopper therefor, a charge-delivering device including a valve 15 controlling the outlet of said hopper, a dumping receptacle in correlation to and operating with said valve to receive the charge therefrom, said valve being normally in closing relation to the hopper outlet and 20 said dumping receptacle in discharging position, and means for actuating said valve to open position and said dumping receptacle to receiving position for the charge as released from said hopper by the valve, said 25 means comprising a normally empty, self-discharging bucket carried by said dumping receptacle, and spring-actuated means, controlled by the pressure of the gas generated in said tank, for supplying a liquid to said 30 bucket, said supply means being maintained normally inactive under a predetermined pressure, whereby, when the pressure decreases, said liquid-supplying means becomes active to fill said bucket to its 35 operative capacity.
4. In a gas generator of the character described, a tank comprising the generator proper, a tank containing a liquid, a pressure-equalizing connection between said two 40 tanks, a liquid conducting pipe extending into said first mentioned tank and communicating with the bottom of said second mentioned tank, a pressure-regulated valve for said conducting pipe controlled by the 45 pressure of the gas generated in said first mentioned tank, and a charge-delivering device in said first mentioned tank, the same comprising a bucket in receiving relation to said conducting pipe and being of a filling 50 capacity to over-balance and actuate said charge-delivering device to deliver the charge.
5. In a gas generator of the character de-

scribed, a charge-delivering device therefor, and automatically operative means for actuating said device, said means comprising a liquid-receiving weight, and means for supplying liquid to said weight, said means being controlled by the pressure of the gas generated in the generator, so as to be maintained normally inactive under a predetermined pressure and become automatically active when the pressure decreases so as to render said weight effective to overbalance said charge-delivering device, and mechanical means for manually operating said charge-delivering device, said last mentioned means having provision for detachable engagement with said charge-delivering device in its operation and permitting independent actuation of the latter in its neutral position.

6. In a gas generator of the character described, a feed hopper, and a charge-delivering device cooperating with the outlet of said hopper, said device comprising a horizontally hinged box having an open end, a transverse valve plate spaced from the bottom and end wall thereof, and a bucket extending from its end wall, said box having a weight for balancing it with its bottom inclined downward with respect to its open end, with said valve plate in closing relation to the hopper outlet, and with said bucket in receiving position, and means for supplying a liquid to said bucket, comprising a delivery pipe having a regulatable, spring-pressed valve controlled by the pressure of the gas in the generator, so as to be normally inactive under a given pressure and become automatically active when the pressure decreases so as to supply the liquid to said bucket to overbalance said charge-delivering device to receive the charge from the hopper as released by said valve plate.

7. In a gas generator of the character described, and according to claim 1, the bucket therein described having a drain to prevent an operative accumulation of the liquid therein in a supply less than the normal minimum working volume.

In testimony whereof, I have hereunto set my hand, this 1st day of November, 1918, at St. Louis, Missouri.

PARMER DORSEY.
